SAFETY RAZOR

Harry Stoney, Watertown, Mass., assignor to
Gillette Safety Razor Company, Boston, Mass.,
a corporation of Delaware

Application January 11, 1934, Serial No. 706,262

14 Claims. (Cl. 30—12)

This invention relates to safety razors of the type in which a flexible and resilient blade is clamped for shaving between members which shape the blade and supply external support therefor adjacent to its cutting edge. For convenience in use it is desirable that the operations of inserting and removing the blade should be such that they may be quickly carried out and that the clamping members may be easily and 5 fully separated to permit the removal or replacement of the blade without obstruction. In one aspect my invention consists in a safety razor having blade clamping members so constructed and arranged that these operations may 10 be effected with a high degree of convenience and with great rapidity. With this end in view, an important feature of my invention consists in a blade-clamping member, herein shown as the cap, comprising co-operating sections mounted 15 for movement into and out of blade-clamping position in rectilinear paths extending transversely to the head of the razor.

One advantage incident to the construction of my invention is that separation of the sections 20 may be effected rapidly and efficiently by bodily movement of the sections from blade-clamping position to open or separated blade-receiving position. For example, the cap sections may be connected to and controlled in their transverse 25 position by a single cam member effective in approximately a quarter turn to move the cap sections throughout their entire range of movement. This is partly due to the fact that by employing a sectional cap of this construction it is 30 unnecessary to cover the entire area of the blade when flexed and clamped in shaving position, but on the other hand, satisfactory results may be secured by clamping the flexed blade in a narrow longitudinal zone located in the vicinity of its 35 cutting edge and the fulcrum shoulders or convex portions of the blade-supporting member or guard. The result is that a relatively short movement of such cap sections is effective fully to expose the entire area of the blade.

Another advantage incident to the construction 40 of my invention is that the blade is flexed by a progressive wedging action of the cap sections and thus requires the application of relatively light pressure in the flexing operation. This 45 is because the transverse rectilinear movement of the cap sections in flexing the blade is substantially greater than the actual flexing displacement of the blade which results in the flexing of the blade being effected under favorable 50 conditions of mechanical advantage.

These and other features of the invention will be best understood and appreciated from the following description of a preferred embodiment thereof, selected for purposes of illustration and shown in the accompanying drawings, in which,— 60

Fig. 1 is a view in perspective of the head of the razor;

Fig. 2 is a view in perspective of the razor as seen from below;

Fig. 3 is a cross-sectional view of the razor on 65 an enlarged scale;

Fig. 4 is a plan view of the head of the razor, with portions broken away;

Figs. 5 and 6 are views in perspective of the 70 individual cap section members;

Fig. 7 is a cross-sectional view on the line 7—7 of Fig. 4;

Fig. 8 is a view in perspective of the guard member;

Fig. 9 is a view of the razor head in longitudinal section on the line 9—9 of Fig. 4; and 75

Fig. 10 is a fragmentary view on a still larger scale showing the relation of a cap section to the blade and to the guard member of the razor.

The guard member 10 is rectangular in outline 80 and provided along its longitudinal edges with guard teeth 12 which extend outwardly slightly beyond the cutting edge of the blade for which the razor is designed. The upper or blade-supporting face of the guard member 10 is provided 85 with longitudinal fulcrum shoulders over which the blade may be flexed when the razor is clamped in position for shaving and with a central longitudinal rib 14 for engaging and accurately locating an internally apertured blade in shaving 90 position. A stem or spindle 16 is formed integral with or otherwise rigidly secured to the guard member 10 and projects downwardly from its lower surface. In each of its end edges the guard member is provided with a transverse groove 95 or guideway 18 and into one end of each guideway projects a stop 20.

The cap section members 22 and 42 comprise open frames designed substantially to enclose the guard member 10. The member 22, as shown in 100 Fig. 6, is provided with a longitudinal bar 24 which constitutes its blade-flexing element of the razor. Its inner face is concave and designed to overlie the upper surface of the blade and flex the blade over one of the fulcrum shoulders of the guard 105 member. The inner face of the bar 24 is provided with curved ribs 26 best shown in Fig. 10, the lower edges of which contact with and flex the blade as the cap section is moved inwardly upon the guard. The cap section member 22 is 110

also provided with transversely projecting guide bars 28 upon both end walls and with a bottom plate 30 from which projects a cam stud 32.

The cooperating cap section member 42 is similarly provided with an overhead bar 44 having ribs 46 on its lower face, with laterally projecting guide bars 48, with a bottom plate 50 and a cam stud 52 projecting downwardly therefrom. The bottom plate 50 of the cap section member 42 is located relatively low in that member and the bottom plate 30 is located relatively high in the member 22, so that the two bottom plates will slide over each other when the two sections are assembled in shaving position. The guide bars 48 of the cap section member 42 are spaced inwardly from the end walls, so as to provide a slot 49 designed to receive telescopically the corresponding guide bars 28 of the cap section 22. The stops 20 in the guideways 18 limit the inward movement of the cap section member 22 by engaging the inner ends of the guide bars 28, while inward movement of the cap section member 22 is limited by the engagement of the guide bars 28 with the inner end of the slot 49 in the cap section member 42. When the cap section members 22 and 42 are assembled upon the guide member 10, they are maintained in sliding relation thereto by the engagement of the guide bars 28 and 48 in the grooves or guideways 18, and the bottom plates 30 and 50 are disposed in sliding superposed relation upon the lower face of the guide member.

The lateral or transverse position of the two cap section members is controlled by the cam studs 32 and 52 which are received in eccentric cam slots formed in a cam plate 54. The cam plate is mounted to rotate about the axis of the stem 16, beneath the guard member 10 and in contact with the bottom plate 50 of the cap section member 42. The cam plate is rigidly secured to the upper end of an operating sleeve 54 journaled upon the stem 16. The cam plate and its operating sleeve 56 are held in place vertically by a lower sleeve 58 which is rigidly secured to the end of the stem 16 by set screws 60. By turning the operating sleeve 56 and the cam plate 54 the cap section members may be moved inwardly or outwardly with reference to each other and the blade flexed and clamped in shaving position or released and exposed for removal from the razor.

As shown in Figs. 4 and 7, the cap section members 22 and 42 occupy their separated position, the sleeve 56 having been turned to the limit of its movement in a clockwise direction as seen in Fig. 4. In this position the blade-flexing bars 24 and 44 are separated to an extent which fully exposes the blade supporting face of the guard member 10, so that the blade 34 may be removed or replaced without interference and it will be noted that in this position both ends of the blade are fully exposed so that they may be conveniently grasped by the fingers of the user.

The razor herein shown is designed for use, among others, with any thin flexible blade having an elongated internal aperture shaped to register with the rib 14 of the guard member and provided with reentrant recesses in its corners which define elongated unsharpened end portions located centrally of the blade. The end walls of the cap sections are slotted outwardly from their inner edges to receive the elongated end portions of the blade 34 and the end edges of the blade extend substantially flush with the outer faces of said end walls. The aperture of the blade, as shown in Fig. 4, is provided with spaced transverse enlargements of various shapes which form

a distinctive outline in the blade visible and more or less ornamental as seen between the blade-flexing bars of the cap sections. For this purpose the bars 24 and 44 are recessed at their inner edges respectively and are provided with end contact projections so that in closed position the caps expose the center portion of the blade.

Assuming that a blade 34 has been placed upon the guard member in the position shown in Fig. 7 with its aperture registering with the rib 14, the sleeve 56 may now be rotated in a counter-clockwise direction whereupon the action of the cam slots upon the cam studs 32 and 52 is to move the cap section members inwardly. In this movement, the blade which has heretofore remained in the flat condition, is engaged by the inclined ribs 26 and 46 of the cap bars 24 and 44 as suggested in Fig. 10 and the blade is flexed over the fulcrum shoulders of the guard member 10. Rotation of the cam plate 54 may be continued until the approaching movement of the two cap section members is positively arrested in the manner already explained. In this position the blade 34 is flexed and clamped in shaving position as shown in Fig. 3. It will be apparent that in this movement the flexing of the blade takes place or is effected in a wedging manner by the inclined edges of the ribs 26 of cap section bars. Accordingly the user is required to exert very little force in clamping the razor for use and the unclamping movement of the cap sections is correspondingly easy. Since there is only this light movement to deal with the pitch or eccentricity of the cam slots in the cam plate 54 may be made steep and the entire movement of the cap section members effected in approximately a turning movement of 90° of the cam plate. The result is that by a very quick, light movement the razor is completely clamped for shaving or opened wide for replacement of the blade.

Having thus described my invention what I claim as new and desire to secure by Letters Patent of the United States is:—

1. A safety razor comprising a guard member shaped to support a flexed blade, and cooperating cap sections guided for movement toward or from blade-flexing position above the guard in rectilinear paths extending transversely of the guard.

2. A safety razor comprising cooperating blade-flexing members, one having a convex face and the other having a concave face, and being mounted for relative sliding movement transversely to the axis of blade flexing.

3. A safety razor comprising cooperating blade-flexing members for a double-edged blade, one having a convex face and the other comprising sections having concave faces and being mounted for equal and opposite rectilinear movement transversely to the axis of blade flexing.

4. A safety razor comprising a guard having a longitudinal blade-flexing face, and cap sections having guide members connecting them for transverse rectilinear movement with said guard below its blade-flexing face and elongated blade-flexing faces disposed above said face.

5. A safety razor comprising a guard having a blade-supporting face, box-shaped cap sections connected to the guard for transverse sliding movement and extending above and below said face, and means for simultaneously moving said cap sections toward or from each other.

6. A safety razor comprising a guard having a blade-supporting face and transverse guideways in its ends, cap sections having guide members

- fitted in said guideways, thus being connected to the guard for transverse movement, and means for moving said cap sections to cover or uncover portions of said blade-supporting face. 80
- 5 7. In a safety razor, a cap section member comprising an open frame including a flat bottom plate, upright side walls, and an overhead blade-flexing bar recessed at one edge and having spaced curved ribs upon its lower face. 85
- 10 8. In a safety razor, a cap section member comprising an open frame including a bottom plate, upright side walls having transverse guides thereon, and a narrow blade-flexing bar disposed in spaced relation to said bottom blade and having spaced curved ribs upon its lower face. 90
- 15 9. A safety razor comprising a blade-supporting member, and a pair of cap sections mounted for transverse sliding movement on said member and having interlocking connections for determining their position of nearest approach. 95
- 20 10. A safety razor comprising a blade-supporting member, box-like cap sections each having a lower portion arranged to pass beneath said member and an upper blade-flexing bar arranged to pass above said member, and means acting on said lower portions to control the transverse position of said sections. 100
- 25 11. A safety razor comprising a blade-clamping member having a convex face for supporting a flexible blade in flat condition thereon, and a 105

- cap section movable in a path parallel to the plane of the blade and having inclined surfaces thereon shaped to contact with the blade and flex it by wedging action upon said convex face. 80
12. A safety razor comprising a blade-clamping member for supporting a flexible blade in flat condition thereon, and cooperating cap sections mounted for transverse rectilinear movement toward each other and each having a blade-flexing bar which bars are spaced from each other to expose the surface of the blade when the cap sections occupy their innermost position above said clamping member. 85
13. A safety razor comprising a blade-clamping member for supporting a flexible blade in flat condition thereon, and cap sections mounted for transverse movement above said member to flex the blade by progressive wedging action an amount less than the movement of the cap sections while in contact with the surface of the blade. 90
14. A safety razor comprising a guard, and cooperating cap sections mounted upon the guard for equal and opposite transverse movement to and from closed, blade-flexing position, the cap sections having end contact projections and being recessed in their inner edges to expose the center portion of the blade when the cap sections are closed. 100
